US0D1040151S

(12) **United States Design Patent** (10) **Patent No.:** **US D1,040,151 S**
(45) **Date of Patent:** ** *Aug. 27, 2024

(54) **SUCTION MOUNT**

(71) Applicant: **Jiaxing Li**, Chongqing (CN)

(72) Inventor: **Jiaxing Li**, Chongqing (CN)

(*) Notice: This patent is subject to a terminal disclaimer.

(**) Term: **15 Years**

(21) Appl. No.: **29/838,880**

(22) Filed: **May 16, 2022**

(51) LOC (14) Cl. **14-03**

(52) U.S. Cl.

USPC **D14/253**; D8/363

(58) **Field of Classification Search**

(57) **CLAIM**

The ornamental design for a suction mount, as shown and described.

DESCRIPTION

FIG. 1 is a perspective view of a suction mount showing my new design;

FIG. 2 is another perspective view of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top view of FIG. 1; and,

FIG. 8 is a bottom view of FIG. 1.

The broken line portions of the suction mount in FIGS. 1-8 represent portions of the suction mount and form no part of the claimed design.

1 Claim, 6 Drawing Sheets
